(57) CLAIM

We claim the ornamental design for a refrigeration compressor, as shown and described.

DESCRIPTION

FIG. 1 is a perspective view of a first embodiment.

FIG. 2 is a front view of the first embodiment.

FIG. 3 is a bottom view of the first embodiment.

FIG. 4 is a left end view of the first embodiment.

FIG. 5 is a top view of the first embodiment.

FIG. 6 is a right end view of the first embodiment.

FIG. 7 is a rear view of the first embodiment.

FIG. 8 is a perspective view of a second embodiment of the

invention, with incidental features illustrated in broken lines.

FIG. 9 is a front view of the second embodiment of the

invention, with incidental features illustrated in broken lines.

FIG. 10 is a bottom view of the second embodiment of the

invention, with incidental features illustrated in broken lines.

FIG. 11 is a left view of the second embodiment of the

invention, with incidental features illustrated in broken lines.

FIG. 12 is a top view of the second embodiment of the

invention, with incidental features illustrated in broken lines.

FIG. 13 is a right view of the second embodiment of the

invention, with incidental features illustrated in broken lines; and,

FIG. 14 is a rear view of the second embodiment of the

invention, with incidental features illustrated in broken lines.

It being understood that the broken lines are for illustrative purposes only and form no part of the claimed design.
